(57) **CLAIM**

The ornamental design for a LED energy-saving bulb (multitube cylinder), as shown and described.

DESCRIPTION

FIG. 1 is a bottom plan view of a LED energy-saving bulb (multitube cylinder) showing my new design;

FIG. 2 is a top plan view thereof;

FIG. 3 is a right side view thereof;

FIG. 4 is a left side view thereof;

FIG. 5 is a front elevational view thereof;

FIG. 6 is a perspective view thereof; and,

FIG. 7 is another perspective view thereof.

The broken lines shown in LED energy-saving bulb (multitube cylinder) form no part of the claimed design.

1 Claim, 7 Drawing Sheets

FIG. 5
